UNITED STATES PATENT OFFICE.

JAMES L. QUIGG, OF RICHMOND, VIRGINIA, ASSIGNOR TO C. F. SAUER COMPANY, OF RICHMOND, VIRGINIA, A CORPORATION OF VIRGINIA.

DESIGN FOR A BOTTLE OR SIMILAR ARTICLE.

56,029.

Specification for Design.

Patented Aug. 10, 1920.

Application filed January 17, 1920. Serial No. 352,220. Term of patent 14 years.

To all whom it may concern:

Be it known that I, JAMES L. QUIGG, a citizen of the United States, residing at Richmond, in the county of Henrico and State of Virginia, have invented a new, original, and ornamental Design for Bottles or Similar Articles, of which the following is a specification, reference being had to the accompanying drawings, forming a part thereof.

The figure is a side elevation of a bottle showing my design.

I claim:

The ornamental design for a bottle or similar article, as shown.

JAMES L. QUIGG.
